Primary Examiner — April Rivas*Assistant Examiner* — Jillian Mazzola(74) *Attorney, Agent, or Firm* — Leydig, Voit & Mayer, Ltd.(57) **CLAIM**

The ornamental design for a character costume, as shown and described.

DESCRIPTION

FIG. 1 is a front perspective view of a character costume showing the new design;

FIG. 2 is a rear perspective view thereof;

FIG. 3 is a front view thereof;

FIG. 4 is a rear view thereof;

FIG. 5 is an atop plan view thereof;

FIG. 6 is a bottom view thereof;

FIG. 7 is a right side view thereof; and,

FIG. 8 is a left side view thereof.

The broken lines in the figures show portions of the character costume that form no part of the claimed design.
